UNITED STATES PATENT OFFICE.

MAURICE COLLMAN, OF AKRON, COLORADO, ASSIGNOR OF ONE-SIXTH TO HARRY COLLMAN, OF AKRON, COLORADO, ONE-SIXTH TO EMMET P. ROGERS, OF DENVER, COLORADO, AND ONE-HALF TO THE INVESTORS SECURITIES COMPANY, OF DENVER, COLORADO, A CORPORATION OF COLORADO.

LIQUID AND GASEOUS FUEL BURNER.

Application filed January 10, 1922. Serial No. 528,184.

To all whom it may concern:

Be it known that I, MAURICE COLLMAN, a citizen of the United States, residing at Akron, in the county of Washington and

5 State of Colorado, have invented certain new and useful Improvements in Liquid and Gaseous Fuel Burners, of which the following is a specification.

This invention appertains to improvements in liquid and gaseous fuel burners generally, and has for its principal object to provide for a type of the same capable of efficient operation in producing maximum heating temperatures from liquid and gaseous fuels of all classes and descriptions, either natural or artificial, such as natural or manufactured gas, alcohol, crude oil, fuel oil, kerosene, or distillates thereof.

Another object of the invention is to provide for a burner of the class mentioned, and one of an extremely simple and comparatively inexpensive construction and arrangement, capable of use as a pre-heating means in welding or dissolving operations 25 on metal and other substances, as well as a heating means for all forms of power boilers, domestic heating boilers or plants, blast furnaces, and for any and all other purposes requiring the application thereto 30 of intense and concentrated heat for their operation at maximum efficiency.

With the foregoing and other equally important objects in view, the invention resides in the certain novel and useful construction and arrangement as will be hereinafter more fully described, set forth in the appended claims, and illustrated in the accompanying drawing, in which:—

Figure 1 is a side elevation, partly in section, of a preferred embodiment of the burner, and,

Fig. 2 is a vertical section taken on the line 2—2 of Fig. 1.

Referring to the drawing, the embodiment of the invention as shown therein comprises a combustion or mixing chamber 10 having the form of an elongated tubular metal body, preferably having its front or upper end 11 of converging or tapered form, and its lower end provided with a pair of diametrically arranged depending arms 12, which also converge one toward the other and support at their free ends, a ring-like

body or collar 13, having a threaded bore 14 passing centrally through the same in line with the longitudinal axis of the bore of the chamber 10.

The burner proper or fuel supply nozzle comprises a straight length of metal stock or pipe 15 having its upper end threaded upwardly through the threaded bore of the collar 13, whereby to discharge directly upward of the bore of the combustion or mixing chamber 10. This nozzle or pipe 15 is formed to provide an upper bore 16 and a lower bore 17, of corresponding diameters, and connected one with the other through the medium of a restricted bore or jet duct 18, the lower bore 17 being of a greater length than the upper bore 16 and passes downwardly through an enlargement 19 formed inwardly of the lower end of the burner pipe 15 and opens outwardly of the extreme lower end of the latter, which is exteriorly threaded below the enlargement 19 for connection to a pipe line (not shown) leading from a source of air or steam supply. Curving outwardly and downwardly from the burner nozzle or pipe 15 is a branch pipe 20, which has its axial bore 21 opening into the upper bore 16 at a point immediately above the upper end of the restricted bore or jet duct 18, and the discharge opening 22 of the bore 21 is preferably of a restricted diameter and is inclined slightly in the upward direction of the bore 16, substantially as is shown in Fig. 2.

The enlargement 19 of the burner nozzle or pipe 15, constituting a valve body or casing, is formed to provide a laterally extended portion 23, which is formed with an axial bore 24 connecting the lower bore 17, and is formed at its inner end to provide a conical seat 25 for the reception of the inner conical end of a needle valve 26 threaded inwardly of the bore 24. The extended portion 23 of the enlargement or valve casing 19, is exteriorly threaded to receive thereon a packing nut 27, carried by the needle valve 25, and acts to compress between its end and the opposed outer end of the extended portion 23, a packing arranged to encircle the latter in a manner to prevent leakage therearound. The outer free end of the needle valve 25 is formed to provide a handle 28, whereby to facilitate the manipulation of

the same for the control of an air or steam supply to the burner. The lower free end of the branch pipe 20 is arranged to have secured thereto, in any suitable manner, a 5 valve casing 29 having a straight axial bore or duct 30 connecting the bore 17, and this casing 29 is formed with an extended or offset portion 31, which, in turn, is provided with an axial bore 32 connecting the bore 10 or duct 30, and is formed at its inner end to provide a conical seat 33 for the reception of the conical end of a needle valve 34. The needle valve 34 is threaded inwardly of the bore 32 and carries a packing nut 35, which is threaded onto the extended or offset portion 31, of the valve casing 29, and acts to compress between the opposed surfaces thereon, a packing 36, whereby to prevent leakage of fuel outwardly of the latter around the needle valve 34. Similarly, the needle valve 34 has its outer free end provided with a handle 37 for facilitating its manipulation in the control and regulation of the amount of fuel to be supplied to the burner.

In the operation of the burner, the lower end of the nozzle or pipe 15 is threaded, as at 38, for connection to a suitable source of air or steam supply (not shown) and 30 the free end of the valve casing 29 is similarly threaded, as at 39, for connection to a suitable source of fuel supply (not shown), and for maximum efficiency, the combustion or mixing chamber 10 is adjusted on the upper end of the nozzle or pipe 15, so that the lower end thereof is disposed in a plane above that of the latter, and at a distance of approximately one-third 35 of its diameter therefrom, as for instance, if the combustion or mixing chamber 10 is two inches in diameter, then the lower end of the same will be spaced at a distance of two-thirds of an inch above the upper discharge end of the burner nozzle or pipe 15. With 40 the burner connected and adjusted, the needle valves 26 and 34 will be manipulated by grasping their handles 28 and 37 to admit air or steam upwardly of the pipe 15 and fuel upwardly of the branch pipe 20. By 45 the peculiar arrangement of the fuel discharge orifice 22, opening from the upper connected end of the branch pipe 20 and into the upper bore 16 of the pipe 15, the fuel is drawn therefrom by the suction or 50 vacuum effects created by the stream of air or steam as it discharges with force or great velocity upwardly of the restricted bore or duct 18, and past the orifice 22, when the fuel mixture is ejected from the upper end of the 55 nozzle or pipe 15 and passes centrally into the combustion or mixing chamber 10, expanding into the form of a very fine spray for the purpose. Ignition of the fuel is preferably accomplished in the space between 60 the upper end of the nozzle or pipe 15 and

the lower end of the combustion chamber 10, and preferably by means of a piece of cotton waste dipped into the liquid fuel, since the flame of an ordinary match would probably be extinguished by the effects of the 70 fuel discharge before such ignition would be affected. Thus the nebulized fuel is converted into flame in the combustion or mixing chamber 10, and the flame issues from its upper converging end 11, while the 75 lower open end of the same affords a free supply of air to support combustion therein. A burner constructed according to this invention can be used for practically all forms 80 of liquid fuel by merely adjusting the two valves 26 and 34, and correspondingly with the degree or quantity of heat required, or the quality or kind of fuel used.

The front or upper end 11 of the combustion or mixing chamber 10 is of converged or tapered form for choking or concentrating the flame in its passage therefrom, and lends extreme high efficiency to the burner for pre-heating purposes, but this convergence or taper may be dispensed with, if 90 desired, without seriously affecting the heating effects obtained, and, in some instances, it will be desirable to so form the upper end 11 of the mixing chamber 10 to act in a manner to spread the flame outwardly therefrom over a relatively large area of surface 95 to be heated.

From the foregoing, it will be readily apparent that, while a preferred embodiment 100 of the burner has been described and illustrated herein in specific terms and details of construction and arrangement, various changes in and modifications of the same may be resorted to without departing from the spirit of the invention, or the scope of 105 the claims appended hereto.

Having thus fully described the invention, what is claimed, is:—

1. A fuel burner comprising a tubular combustion chamber open at both ends, a 110 fuel supply nozzle disposed rearwardly of one of the open ends of said chamber and spaced therefrom, means for adjustably connecting said nozzle with said chamber, a fluid supply element disposed in the same 115 plane as the plane of the nozzle and further formed integral with the nozzle, said fluid supply element at its point of joinder with said nozzle provided with a restricted duct to increase the velocity of the supply of fluid 120 to the nozzle, a curved branch pipe having one end formed integral with said nozzle forwardly of said duct and formed with a restricted outlet opening into said nozzle, and said fuel supply element positioned in 125 parallelism with respect to said fluid supply element, and opening into said pipe.

2. A fuel burner comprising a tubular combustion chamber open at both ends, a fuel supply nozzle disposed rearwardly 130

of one of the open ends of said chamber and spaced therefrom, means for adjustably connecting said nozzle with said chamber, a fluid supply element disposed in the same plane as the plane of the nozzle and further formed integral with the nozzle, said fluid supply element at its point of joinder with said nozzle provided with a restricted duct to increase the 10 velocity of the supply of fluid to the nozzle, a curved branch pipe having one end formed integral with said nozzle forwardly of said

duct and formed with a restricted outlet opening into said nozzle, said fuel supply element positioned in parallelism with respect to said fluid supply element, and opening into said pipe, means carried by the fluid supply element for controlling the supply therethrough, and means carried by the fuel supply element for controlling the supply therethrough. 15 20

In testimony whereof I affix my signature hereto.

MAURICE COLLHAN.
